UNITED STATES PATENT OFFICE.

FRANCIS LEE STUART, OF NEW YORK, N. Y.

APPARATUS FOR CONVEYING, DELIVERING, AND GATHERING MATERIAL.

1,397,561.

Specification of Letters Patent.

Patented Nov. 22, 1921.

Application filed June 18, 1920. Serial No. 389,879.

To all whom it may concern:

Be it known that I, FRANCIS LEE STUART, a citizen of the United States, residing at New York city, in the county and State 5 of New York, have invented certain new and useful Improvements in Apparatus for Conveying, Delivering, and Gathering Material, of which the following is a specification.

10 This invention relates to apparatus for carrying material brought from a distance by a main conveyer belt to a pile or place for storage or delivery, and also to apparatus for gathering material and depositing it on a conveyer belt which carries it to a distant point. Apparatus of this general kind is shown in my United States Patent No. 1,325,812 of December 23, 1919. In that patent I have shown a tripper associated with a main conveyer belt which delivers to a boom conveyer which in turn discharges the material from its outer end and piles or stacks it. The boom conveyer carries a grab bucket equipped with suitable operating devices, by means of which the material may be gathered and deposited on the main conveyer belt and conveyed to a distant point or discharged wherever desired.

20 According to my present invention I provide a combined stacker and gatherer in which the grab bucket instead of being supported by the boom conveyer is hung from the outer end of the boom of a crane, and 25 the boom conveyer is mounted to extend through the crane boom and is supported thereby at a considerable distance from its pivoted inner end. The boom conveyer is equipped with rollers which operate in 30 guides in the crane boom so that while the outer portion of the stacker boom is supported by the crane boom, the former may be raised and lowered by the crane boom when the latter is moved vertically and a 35 pivotal connection is provided between the stacker boom and the crane boom which permits of the relative movements of the two booms while they are being moved. In this way I provide a combined stacker and crane 40 of simple but efficient construction and which may be easily operated.

In the accompanying drawings:—

Figure 1 is a side elevation of a combined stacker and gatherer embodying my improvements.

Fig. 2 is a detail view on an enlarged

scale and in side elevation of the outer end of the apparatus.

Fig. 3 is a plan view of the apparatus shown in Fig. 1.

Fig. 4 is a plan view on an enlarged scale of the lower part of the apparatus, with crane boom and stacker omitted.

Fig. 5 is a view on an enlarged scale and in side elevation of parts of the mechanism.

A main conveyer belt A, which may be of any desired length to convey material from a distant source of supply, is provided with a looped portion or tripper A' supported by a frame B mounted on a truck C, the wheels c of which traverse a track D running parallel with the main conveyer belt. The belt A passes over a delivery roller a at the top of the frame B and thence passes to drive pulleys E and F 75 to which power is applied by a motor G. Thence the belt passes over a tension pulley H and then forward as indicated. The pulley H is carried by a suitable frame to which is connected a rope J extending over 80 a pulley j and thence over a pulley k and carries a counterweight K. By this mechanism the desired tension is given to the tripper and main conveyer belt. The mechanism just described is substantially the same 85 as that shown in my United States Patent No. 1,317,997 of October 7, 1919.

The tripper delivers through a hopper L to the inner end of a conveyer belt m on the stacker boom M. The belt m is 90 driven by motor mechanism N and the stacker boom is pivoted at n to a frame O carried by a turntable P which is mounted on a truck Q, the wheels q of which traverse the track D. The truck Q is connected 95 with the wheel supported frame B which carries the tripper in any suitable way.

The stacker boom in this instance is not provided with means at its inner end for raising and lowering it, as a different mechanism is used for this purpose. By the mechanism shown and as thus far described, material may be conveyed by the belt A and delivered through the hopper L to the conveyer of the stacker boom from the outer 105 end of which the material may be discharged, and as the stacker is supported by a turntable, the material may be delivered in any desired vertical plane.

The crane boom R is pivoted at its lower 110 end to the turntable P at r and is free to turn about a horizontal axis so that its outer

end may be raised and lowered to any desired extent. Said crane boom supports a gathering device S, in this instance a grab bucket of well known construction, which 5 is operated by a rope T connected with a windlass t operated by suitable motor mechanism t' on the truck. The crane boom is raised and lowered by a rope U connected at u with the outer end of the crane boom 10 and extended to a motor operated windlass V on the turntable P. The motors V' are geared as shown at v to a shaft v', which is geared at v² to mechanism for rotating the turntable. The crane boom is of skeleton 15 construction and has a longitudinal opening in it through which the stacker boom extends. The outer portion of the stacker boom is equipped with rollers x which traverse guides x' on the crane boom, the arrangement being such that as the crane boom is raised and lowered the stacker boom is also correspondingly moved and is at all 20 times supported and braced near its outer end or at a considerable distance from its 25 pivotal connection with the truck.

By the mechanism shown the crane boom may be set at any desired angle relatively to the ground level and will correspondingly raise and lower the stacker boom which may 30 thus be set to deliver from any desired horizontal level or at any desired distance from the ground. Inasmuch as the crane boom is supported by the turntable and as the stacker boom is connected with the crane boom to move with it sidewise or about a vertical axis, the crane boom may be set to 35 deliver material at any desired vertical plane. It will be observed that when the turntable is moved about its axis it not only moves the stacker boom sidewise by reason 40 of the connection between the inner end of the stacker boom and the frame of the turntable, but a sidewise movement is imparted to the outer portion of the stacker boom by 45 reason of its connection with the crane boom.

An important feature of the invention consists in pivotally connecting the inner end 50 of a stacker boom to a turntable and in supporting the outer portion of the stacker boom by another boom which is connected to the turntable below the pivotal connection of the stacker boom with the turntable. Such construction is simple and efficient and provides novel means for supporting and bracing 55 the outer portion of the stacker boom, which in some cases is of great length. This feature of my invention is believed to be novel whether or not said supporting boom is used to support gathering mechanism.

60 The gathering device S may deliver material wherever desired, as to a hopper W,

which may discharge onto the main conveyer belt as described in my Patent No. 1,325,812 of December 23, 1919, above mentioned.

I claim as my invention:

65 1. An apparatus for delivering material, comprising a truck, a turntable thereon, a vertical frame on the turntable, a stacker boom equipped with a conveyer and pivotally connected at its inner end with the frame on the turntable to move about the horizontal axis, a main conveyer belt delivering to the stacker boom, and a boom connected with the outer portion of the stacker boom at a considerable distance from its pivotal connection with the turntable and which is pivotally connected with the turntable below the inner end of the stacker boom.

70 2. A combined stacker and gatherer, comprising a truck, a turntable thereon, a crane boom pivotally connected with the turntable to move about a horizontal axis, gathering mechanism carried by the crane boom, means on the turntable for operating said gathering mechanism, means on the turntable for raising and lowering the crane boom, a main conveyer belt equipped with a tripper, a stacker boom provided with a belt to which the tripper delivers, a pivotal connection between the stacker boom and the 75 turntable permitting the stacker boom to move about a horizontal axis, and sliding connections between the outer portion of the stacker boom and the crane boom whereby the outer portion of the stacker boom is supported by the crane boom and the stacker boom is raised and lowered by said crane boom.

80 3. A combined stacker and hoisting crane, comprising a truck, a turntable thereon, a crane boom pivotally connected with the turntable to move about a horizontal axis, gathering mechanism carried by the crane boom, means for operating said gathering mechanism and for raising and lowering the 85 crane boom, and a stacker boom pivotally connected with the turntable at its inner end and slidably connected at its outer portion with the crane boom.

90 4. A combined stacker and hoisting crane comprising a truck, a crane boom mounted to turn about a horizontal axis, gathering mechanism carried by the crane boom, means for operating said gathering mechanism and for raising and lowering the crane boom, a 95 stacker boom extending through the crane boom and pivoted to move about a horizontal axis, and means for raising and lowering the stacker boom.

100 In testimony whereof, I have hereunto 105 subscribed my name.

FRANCIS LEE STUART.
